CLAIM

(21) Appl. No.: **29/235,577**

The ornamental design for a combined ceiling fan motor housing and light kit, as shown and described.

(22) Filed: **Aug. 4, 2005**

DESCRIPTION

(51) **LOC (8) Cl. 23-04**

FIG. 1 is a perspective view of a combined ceiling fan motor housing and light kit showing my new design;

(52) **U.S. Cl. D23/377; 23/379; 26/59**

FIG. 2 is a front end elevation view thereof;

(58) **Field of Classification Search** D23/377, D23/379, 385, 411, 413; 416/5; D26/59, D26/72, 81-88, 51

FIG. 3 is a rear end elevation view thereof;

See application file for complete search history.

FIG. 4 is a left side elevation view thereof;

(56) **References Cited**

FIG. 5 is a right side elevation view thereof;

U.S. PATENT DOCUMENTS

FIG. 6 is a top plan view thereof;

D421,799 S * 3/2000 Zuege D23/377
D464,424 S * 10/2002 Campbell D23/411

FIG. 7 is a bottom plan view thereof; and,

FIG. 8 is a reduced front end view of the combined ceiling fan motor housing and light kit in accordance with my design, shown in its environment.

The broken lines in FIG. 8 shows environmental features, which are for illustrative purposes only and form no part of the claimed design.
